UNITED STATES PATENT OFFICE.

CHARLES P. SKUBLIN, OF DETROIT, MICHIGAN, ASSIGNOR TO WILLIAM A. ADAMS,
OF DETROIT, MICHIGAN.

GAS-ENGINE.

1,345,266.

Specification of Letters Patent. Patented June 29, 1920.

Application filed November 15, 1918. Serial No. 262,661.

To all whom it may concern:

Be it known that I, CHARLES P. SKUBLIN, a citizen of Russia, residing at Detroit, county of Wayne, State of Michigan, have 5 invented a certain new and useful Improvement in Gas-Engines, and declare the following to be a full, clear, and exact description of the same, such as will enable others skilled in the art to which it pertains to 10 make and use the same, reference being had to the accompanying drawings, which form a part of this specification.

My invention relates to an improvement in internal combustion engines, shown in 15 the accompanying drawings and more particularly pointed out in the following specification and claims.

This invention is designed as an improvement on that shown and described in 20 United States Letters Patent No. 1250683, issued to me December 17, 1917.

One of the objects of the present invention is to provide a single rotary valve adapted to control both the inlet and 25 exhaust ports of the several cylinders of an engine.

Another object of the invention is to construct the valve with an annular passage through which the combustible mixture may 30 be delivered to the respective cylinders of the engine, the valve having also a central longitudinal passage, through which the exhaust gases from the several cylinders are discharged; a non-heat conducting material 35 being interposed between the central and surrounding annular passage to prevent the expansion of the valve in the valve chamber that it may not become "bound" therein.

Another object of the invention is the 40 means employed for lubricating the valve, the construction being such that it will not operate to "flood" the cylinders with oil.

Another feature of the invention is the 45 means provided for draining back all surplus oil to the crank-case.

With the foregoing and other objects in view, which will appear as the description proceeds, the invention resides in the combination and arrangement of parts and in 50 the details of construction hereinafter described and claimed, it being understood

that changes may be made in the precise embodiment herein disclosed without departing from the spirit of the invention.

In the accompanying drawings:—

55

Figure 1 is a longitudinal horizontal sectional view through the engine and valve chamber.

Fig. 2 is an end elevation of the engine showing the crank shaft connection for operating the valve.

60

Fig. 3 is a vertical cross-sectional view on line 3—3 of Fig. 1, showing parts in elevation, the valve being positioned as it would appear on the suction stroke.

65

Fig. 4 is a similar view with the valve positioned as on the compression stroke.

Fig. 5 is a like sectional view with the valve positioned as when the explosion occurs.

70

Fig. 6 is a fragmentary longitudinal vertical sectional view through the valve, showing the oil duct, oil inlet and discharge pipe connections, and oil overflow pipe.

75

Fig. 7 is a diagrammatic view indicating a single rotation of the valve and its chronological order of operation.

Referring now to the letters of reference placed upon the drawings:—

A, denotes the crank case of the engine, B, 80 its cylinders and C, their water jackets. D, designates a crank-shaft journaled in the crank-case. E, are pistons, and F, are rods connecting the pistons with the crank-shaft.

G, is a longitudinal tapering valve supported in a valve chamber G¹ connected by suitable ports in the valve chamber with the respective cylinders inclosed by a water jacket C¹ communicating with the water jacket C of the cylinders.

85

Intermediate of the ends of the valve chamber is an intake connection H, to which a carbureter I may be attached as shown in Fig. 2 of the drawings.

Extending longitudinally within the 95 valve is an exhaust passage g for two of the engine cylinders, divided by a longitudinally extending cross partition g¹, forming an exhaust passage g² for the other cylinders; both passages communicate at the 100 enlarged end of the valve with a casting K, bolted thereto, having radial openings K¹,

90

for the delivery of the exhaust gases into the chamber G^2 , from which they are discharged through the opening G^3 .

g^3 are radial ports adapted to successively communicate with the cylinder ports B^1 , through which the combustible mixture is delivered to the cylinder, and the exhaust gases discharged therefrom.

g^a is an annular longitudinal passage in 10 the valve having an intermediate peripheral channel g^b for communication with the carburetor I , and with radial ports g^c , for the delivery of the combustible mixture to the ports B^1 , leading to the respective cylinders.

L , denotes a non-heat conducting insulation between the walls of the annular passage g^a through the valve and its central exhaust passage g ; that the valve may not expand and "bind" in its chamber through the heat produced by the exhaust gases passing therethrough.

M , is a longitudinal well or duct extending the length of the valve having one of its 25 side walls M^1 inclined in the direction of the rotation of the valve. At each end of the chamber are pipes N , N^1 for the delivery of oil from the crank-case to the duct M , and its return to the crank-case. The oil being 30 delivered to the oil duct at the contracted end of the valve chamber through a pipe N flows down the duct through the opening G^4 in the intermediate wall G^5 (closing the peripheral gas inlet channel g^b from the 35 oil duct M) and passes back to the crank-case through the pipe N^1 .

P , designates a suitable oil pump actuated from the crank-shaft for delivering oil to the duct M . Q , denotes an auxiliary overflow pipe for conducting any surplus oil back to the crank-case, thus relieving any pressure caused by the action of the pump, and thereby providing against the cylinders becoming flooded with oil.

45 R , is a worm gear keyed to the valve stem G^2 , actuated by a suitable driving connection S , in turn operated by the engine crank-shaft. T , denotes a spring sleeved on the valve stem and bearing against the end 50 wall of the valve chamber and against the gear R , to maintain the valve in an intimate contact relationship with the wall of the valve chamber.

55 U , designates the spark plugs of the respective cylinders.

It will now be understood that the rotation of the valve is relatively slow,—as the several operations of the respective cylinders known as "suction" "compression", "explosion" and "exhaust" are served upon each 60 revolution of the valve,—the wear of parts is thus materially decreased.

The longitudinal oil duct is of sufficient width and provided with an inclined wall on

one side in order that any surplus oil that 65 may have entered the radial ports in the valve can drain back into the oil duct as the valve rotates into juxtaposition with the wall of the valve chamber following the passage of said oil duct.

70 By providing the valve with inlet and exhaust passages adapted to control the delivery of the combustible mixture and the discharge of its burnt gases through the same ports of the respective cylinders, the 75 cost of manufacture has been reduced and the simplicity of its operation has been materially increased. So also by providing a non-heat conducting insulation between the inlet and the exhaust passages through the 80 valve, the expansion of the valve and consequent "binding" of the same in the valve chamber has been overcome.

Having thus described my invention, what I claim is:

85 1. The combination with an internal combustion engine comprising a plurality of cylinders, a tapering valve chamber having channels leading to all of the cylinders, a tapering rotary valve in said valve chamber 90 having an annular longitudinal channel with ports adapted to successively register with the channels leading to the respective cylinders for delivery of an explosive mixture thereto, the tapering valve being provided with a tapering central longitudinal passage having a division plate extending for a portion of its length to form compartments in said central passage, radial ports in both compartments of said central passage adapted to be brought into registration with the channels connected with the cylinders for discharge of the burnt gases therefrom, and means actuated by the crank-shaft of the engine for rotating said valve. 100

95 2. The combination with an internal combustion engine comprising a plurality of cylinders, a tapering valve chamber with channels leading to the respective cylinders of the engine, a tapering valve fitted to said 110 tapering valve chamber having passages with radial ports adapted respectively for the delivery of a combustible mixture to the cylinders and the discharge of the burnt gases therefrom, means for rotating said valve, a longitudinal inclined oil well in said tapering valve chamber extending substantially the length thereof, means for delivering oil from the crank-case of the engine to the longitudinal oil well, the oil 120 adapted to be passed down the oil well by gravity, and means for returning the surplus oil from the oil well back to the crank case.

125 3. The combination with an internal combustion engine comprising a plurality of cylinders, a tapering valve chamber with channels leading to the respective cylinders of

the engine, a tapering valve fitted to said tapering chamber having passages with radial ports adapted to successively register with the channels leading to the cylinders for the passage of a combustible mixture thereto and the discharge of the burnt gases therefrom, a longitudinal oil well extending substantially the length of the valve chamber having one wall or bank inclined to al-

low the return of the oil back from the valve 10 when excess oil has entered same.

In testimony whereof, I sign this specification in the presence of two witnesses.

CHARLES P. SKUBLIN.
